[57] CLAIM

The ornamental design for a combined ceiling fan and light, as shown and described.

DESCRIPTION

FIG. 1 is a perspective view of a combined ceiling fan and light showing my new design;

FIG. 2 is a bottom elevational view thereof;

FIG. 3 is a top elevational view thereof; and,

FIG. 4 is a side view thereof, the other sides being identical to that shown except for the position of the fan blades.
